UNITED STATES PATENT OFFICE.

THOMAS GILMORE, JR., OF BROOKLYN, NEW YORK, ASSIGNOR TO GENERAL BRIQUETING COMPANY, OF NEW YORK, N. Y., A CORPORATION OF MAINE.

BRIQUETING-MACHINE.

1,247,667.

Specification of Letters Patent. Patented Nov. 27, 1917.

Application filed February 6, 1917. Serial No. 146,873.

To all whom it may concern:

Be it known that I, THOMAS GILMORE, Jr., a citizen of the United States, and resident of the borough of Brooklyn, county of Kings, city and State of New York, have invented certain new and useful Improvements in Briquetting-Machines, of which the following is a specification.

My invention relates to briquetting machines or presses and more particularly to machines or presses for briquetting metal or mineral fines through the medium of pressure and without the use of a binder of any kind. My improvement has for its object to provide a simple machine of the indicated type wherein the process of briquetting is efficiently carried out, which works at low tonnage capacity and wherein the well known advantages of briquetting are brought within the reach of smaller foundries and industrial plants ordinarily incapable of installing and supporting the high capacity, expensive machines heretofore found necessary to secure proper working. A further object of my invention is to provide a briquetting machine in which the difficulties of feeding the material, packing it preparatory to the use of heavy pressure and removal of the finished briquets from the machine which ordinarily exist in such machines, are entirely overcome or at least reduced to a minimum. Other objects of my improvement will appear from the description hereinafter and the features of novelty thereof will be pointed out in the appended claims.

In the accompanying drawings, which show an example of my invention for illustrative and descriptive purposes, Figure 1 is a plan view of my machine; Fig. 2 is a side elevation partly in section; Fig. 3 is a cross section on the line 3—3 of Fig. 2 and Fig. 4 is a similar view on the line 4—4 of Fig. 2.

As shown in the illustrated example the machine or press comprises a pressure exerting mechanism 5 which may be of any suitable and well known type in which the pressure is subject to the desired control by the operator in any suitable manner. The mechanism 5 as shown may be connected with a source of power, preferably though not necessarily hydraulic, by means of a pipe 6, said mechanism controlling and operating a plunger 7 of suitable dimensions and material and having a pressure exerting or oper-

ative end 8; as shown in the drawings a cross-head 7^a and its co-operating parts may be operatively connected with the plunger 7. The machine further includes a full mold 9 carried by suitable supporting means 9^a, and 60 corresponding in cross-sectional form to the shape of the operative end 8 of the plunger 7. The illustration shows these elements as cylindrical which it is to be understood is not essential as any other desired form of 65 construction may be substituted. In any case the operative end 8 of the plunger 7 is of a size adapted to fit the mold 7 snugly or with what is commonly known as a sliding fit, the mold 7 being preferably provided 70 with a lining 10 of suitable material adapted to resist wear and reduce friction to a minimum. A movable plate 11 normally forms the back of the mold 9 and controls the communication between the latter and an exit 75 or discharge channel 12 as shown in Fig. 2. The plate 11 may be operated in the manner and for the purpose to be more fully described hereinafter in any suitable manner as for instance by means of a lever 13 80 pivotally mounted upon a rod 14 carried by lugs 15 forming part of or secured to the mold support 9^a and pivotally connected at 16 with the plate 11. In order to facilitate the operation of said plate 11, the lever 13 85 may be provided with a counterweight 17 preferably adjustable thereon and secured in its adjusted position by friction or in any other suitable manner. The mold support 9^a and the pressure exerting mechanism 5 90 in the illustrated example are connected together in spaced relation to each other and against separation by means of bolts 18 and nuts 19, the bolts being located at opposite sides of the plunger 7 in parallel relation 95 with each other and with said plunger.

The machine further comprises a packing device which in the example shown comprises a trough or receptacle 20 of semi-circular shape in cross-section and secured at 100 its one end to said mold support 9^a and at its other end to a cross-bar 21 extending between and carried by the bolts 18. The cross-bar 21 may be fixed upon the bolts 18 in any desired manner as by means of clamping devices 22 and in any case preferably extends beneath the plunger 7 so as not to interfere with the operation thereof. The packing device referred to further consists of a movable cover 23 which in the illus- 110

trated example is also semi-circular in cross-section and fits upon the trough or receptacle 20. In the operative condition of the machine the combined trough or receptacle 20 and movable cover 23 together form a hollow cylinder located in axial alinement with the mold 9 and plunger 7 and in which the latter fits perfectly or in other words with a sliding fit. It will of course be understood, if the shape of the plunger end 8 and mold 9 is other than circular, that the trough or receptacle 20 and cover 23 are constructed to form a cylinder having a corresponding cross-sectional form as will be apparent.

The cover 23 may be movable relatively to the trough 20 in any desired manner and as shown is pivoted at 24 upon lugs 25 secured to or forming part of the trough 20 or cross-bar 21; in order to operate the cover 23 it may be formed or provided with a projection 26 to which arms 27 are secured for instance by means of bolts 28, said arms 27 in the illustrated example inclining upwardly and diverging from said projection as shown in Figs. 1 and 2. In order to facilitate the actuation of the cover 23 if supported and operated as shown in the illustrated example the arms 27 may be provided with counter weights 29 preferably adjustable thereon and secured in position in any suitable manner as by means of set screws 30. Any means suitable for the purpose may be used to lock the cover 23 in its operative position against movement relatively to the trough 20; for instance as shown the latter may be provided with upright lugs 31 between which a transverse projection 32 secured to or formed on the cover 23 fits in the operative position of the latter. The lugs 31 and projection 32 are formed with apertures adapted to register with each other in the operative position of the parts and are arranged to accommodate and receive a bolt 33 which when in position, serves to lock the cover 23 in operative combination with the trough 20. It will be apparent that the above are only examples and that the cover 23 may be otherwise movable relatively to the trough 20 than as shown and described and also other types of locking devices either manually actuated or by means of suitable power may be substituted if desired. In order to increase the rigidity and strength of the cover 23 it may be provided with a rib 34 extending between the projections 26 and 32 as shown in Fig. 1.

When operatively set up the pressure exerting mechanism 5 and mold 9 with its connected parts rest upon a suitable foundation 35, with the common axis of the mold 9, cylinder formed by the trough 20 and cover 23, plunger 7 and mechanism 5 extending in a horizontal direction, the exit or discharge channel 12 preferably inclining

downwardly as shown in Fig. 2 to facilitate the ejection of the finished briquet. In the position of rest and assuming that the full capacity of the trough 20 is desired, the operative end 8 of the plunger 7 is located in said trough 20 at or near the free end thereof as shown in Fig. 2 so as to free the latter substantially throughout its entire length while the plate 11 is in its operative position to close the one end of the mold 9. When the machine is operatively used the bolt 33 is first removed to unlock the cover 23 which is then swung upon its pivot 24 through the medium of the arms 27 to the position indicated by dotted lines in Fig. 2; in this position the interior of the trough or receptacle 20 is exposed substantially throughout its entire length, the plunger 7 being drawn back as before stated and as also shown in said Fig. 2. The material to be briquetted, for instance metal or mineral fines, is then fed into said trough either manually or by means of any suitable feeding device until the desired amount has been reached. The cover 23 is then returned to its normal position and locked therein by means of the bolt 33 or other locking means, this operation causing said cover 23 to press down upon the material in the trough 20 and forming a fairly well packed mass. The mechanism 5 is now operated to cause the plunger 7 to move forward into the cylinder formed by the trough 20 and cover 23 at a moderate pressure whereby the material is slowly forced from said cylinder and slowly packed into the mold 9 against the plate 11, the speed of operation being so gaged as to allow the escape of air from said material. When the material has all been pushed or transferred from said cylinder to the mold 9, full pressure is exerted upon the plunger 7 until a solid, homogeneous briquet of even density is formed and a perfect set of the material is obtained.

As soon as this result has been accomplished pressure is removed from the plunger 7 to relieve the plate 11 which is then raised by means of the lever 13 and counterweight 17 to establish communication between the mold 9 and the exit or discharge channel 12. The plunger 7 is then again set in motion or caused to move forward in a manner to bring sufficient pressure upon the finished briquet to eject it from the mold 9 into the discharge channel 12 from which it may pass to a suitable support, receptacle or the like. After the finished briquet has been fully ejected the plate 11 is again returned to operative position to close the exit end of the mold 9 and the plunger 7 is drawn back until its end 8 is again located at or in close proximity to the free end of the cylinder formed by the trough 20 and cover 23. It will, of course, be understood, if the full capacity of the trough 20 is not desired, for

instance because of the initial density of the material which is to be briqueted, that the plunger 7 need not be fully withdrawn to the position shown and described in the illustrated example. In other words, the plunger, in its position of rest or at the start may occupy an intermediate position in said trough in which case only a part of the capacity thereof is made use of. Suitable 10 adjustable stops may be provided in the mechanism 5 for coöperation directly with the plunger 7 or the cross-head 7^a to pre-determine the position of rest of said plunger. This starting position is always determined by the initial density of the material and thus prevents overloading of the mold 9. After the plunger 7 has reached its position of rest the cover 23 is again swung to its open position to permit the receptacle 20 or trough 20 to be again filled after which the described operation is repeated, this sequence being continuously repeated throughout the operation of the machine. During the operation of the machine the locked 25 cover 23 and the close, sliding fit of the end 8 of the plunger 7 forces the material in its entirety to move forward into the mold 9 and prevents any transverse or other unintentional spread thereof.

30 My improved machine in the preferred form operates entirely in a substantially horizontal direction and is thus capable of producing briquets of maximum quality while working efficiently at low tonnage capacity. My improved machine also provides for readily feeding the material thereto and for efficiently packing it prior to the use of the heavy pressure whereby the actual briquetting is accomplished and in 35 addition provides for the removal of the finished briquet from the machine in a simple and efficient manner and without danger of injuring the briquet itself.

Furthermore my improved machine 40 avoids the necessity for high capacity and expensive installations heretofore generally necessary to secure proper working and thus brings the many and well known advantages of briquetting within the reach of 45 small foundries and industrial plants which usually are unable to stand the expense connected with the installation and operation of such machines. My machine may be efficiently utilized for briquetting many kinds 50 of material and is particularly adapted for briquetting metal or mineral fines without the use of a binder of any description.

Various changes in the specific form 55 shown and described may be made within the scope of the claims without departing from the spirit of my invention.

I claim:—

1. A briquetting machine comprising a 60 mold, means for receiving the material to be briqueted, means for packing said mate-

rial in said receiving means, and means for transferring said packed material from said receiving means to said mold and for compressing it therein to form a briquet, said mold, receiving means and compressing 70 means being located in substantial horizontal, axial alinement.

2. A briquetting machine comprising a 75 mold, means for receiving the material to be briqueted, means for packing said material in said receiving means and a plunger for transferring said packed material from said receiving means to said mold and for compressing it therein to form a briquet and for ejecting the finished briquet from the 80 machine.

3. A briquetting machine comprising a 85 mold, means for receiving the material to be briqueted, means coöperating with said receiving means to form a complete container for said material in communication with said mold and for packing said material, a plunger slideable in said container and movable into said mold whereby said packed material is transferred from the 90 container to the mold and compressed therein to form a briquet and means for actuating said plunger.

4. A briquetting machine comprising a 95 mold, a discharge channel communicating therewith, movable means forming a wall of said mold and controlling the communication between said mold and discharge channel, and means for compressing a material in said mold to form a briquet and for 100 ejecting the finished briquet from said mold to said discharge channel.

5. A briquetting machine comprising a 105 mold, a fixed receptacle arranged to receive the material to be compressed, a movable cover coöperating with said receptacle to form a tubular container communicating with said mold, a plunger slideable in said container whereby said material is transferred therefrom to said mold and compressed therein to form a briquet and means for actuating said plunger.

6. A briquetting machine comprising a 110 mold, a movable plate arranged to close one end of said mold, means for actuating said plate to open and close said end, a trough 115 extending in axial alinement with said mold for receiving the material to be briqueted, a movable cover for packing said material in said trough and coöperating therewith to form a tubular container communicating with said mold, a plunger whereby said material is transferred from said container to said mold and compressed therein against said plate to form a briquet and whereby 120 the finished briquet is ejected from the machine when said plate is open and means for operating said plunger.

7. A briquetting machine comprising a 125 mold, a movable plate arranged to close one 130

end of said mold, means for actuating said plate to open and close said end, a trough extending in axial alinement with said mold for receiving the material to be briqueted, a 5 movable cover for packing said material in said trough and coöoperating therewith to form a tubular container communicating with said mold, means for locking said cover in its closed position, a plunger whereby 10 said material is transferred from said container to said mold and compressed therein against said plate to form a briquet and whereby the finished briquet is ejected from the machine when said plate is open and 15 means for operating said plunger.

8. A briquetting machine comprising a mold, a movable back plate therefor, means for receiving the material to be briqueted, and a plunger operated at reduced pressure 20 to transfer the material from said receiving means to said mold and at increased pressure to compress the material in the mold against said back plate to form a briquet, said plunger being relieved from pressure 25 to permit said back plate to be opened and being again operated at reduced pressure to eject the finished briquet from the machine.

In testimony whereof I have hereunto set my hand.

THOMAS GILMORE, JR.
